J. A. HAGSTROM

HOT AIR FURNACE

Filed Aug. 9, 1923

John A. Hagstrom
INVENTOR

BY *John A. Hagstrom*
ATTORNEY

UNITED STATES PATENT OFFICE.

JOHN A. HAGSTROM, OF YOUNGSTOWN, OHIO.

HOT-AIR FURNACE.

Application filed August 9, 1923. Serial No. 656,472.

To all whom it may concern:

Be it known that JOHN A. HAGSTROM, a citizen of the United States of America, residing at Youngstown, in the county of Mahoning and State of Ohio, has invented certain new and useful Improvements in Hot-Air Furnaces, of which the following is a specification.

This invention relates to what is known to the trade as hot air furnaces. The principal object of this invention is to provide a furnace reasonably simple in construction and particularly efficient in producing heat with a minimum amount of fuel.

Another object of this invention is to provide a furnace having the fire pot divided by means of a preheated air manifold.

A still further object is to provide means for admitting overhead air at both sides of chambers arranged above the fuel line of said furnace.

Another object is to provide a secondary outlet to a chimney or flue for said furnace.

A still further object is to provide an upper chamber having a secondary chamber arranged so as to regulate the gases produced by the burning fuel within said furnace in relation to its final exit to an outlet leading to a chimney or flue for said furnace.

In order that the present invention may be more readily comprehended, I have disclosed one embodiment of the same in the accompanying drawings, though it is to be understood that these drawings are merely illustrative and that the contemplated structure is susceptible of a wide range of variation and modification without departing from the spirit of the invention or sacrificing any of the salient features or underlying principles thereof.

Ordinary furnaces known to the trade make no special provision for consuming the smoke that usually finds its way up the chimney. With the construction which is about to be set forth, it is believed that the incompletely combustion of fuels which ordinarily go up the chimney in the form of combustible gases, carbon and smoke will be utilized in providing heat and thus saving fuel.

In the drawings:

Figure 1 is a front elevation of the furnace.

Figure 2 is a top plan view of a lower section of the furnace.

Figure 3 is a top plan view of a second section resting upon the lower section.

Figure 4 is a top plan view of a top section of the furnace showing the upper covering of the same removed.

Figure 5 is a detailed view showing curved and slotted partitions, shown in Figure 3.

By referring to Figures 1 and 2 it will be seen that I have provided a lower section 1 equipped with grates 2 and 3. There is also provided an ash pit 4 underneath the grates having clean out doors 5. Centrally located within the lower section 1 and between the grates 2 and 3 there is provided a hot air manifold 6 provided with a plurality of openings 7. These openings 7 are formed in the ridge portion of the upper part 8 of the hot air manifold 6. It will also be seen that there is a fresh air inlet 9 connecting with the rear end of the hot air manifold 6.

By referring to Figure 3 it will be seen that I have provided a second section 10. This section 10 is semi-elliptical in shape and provided with an interior circular member 11 which fits directly over the lower section 1. This interior circular section 11 is provided with curved and slotted partitions 12 and 13 which are formed in two sections for the convenience of inserting or removing the same (see Fig. 5). These curved and slotted partitions allow waste gases and smoke to pass into chambers 14 and 15 formed at the ends of the second section 10. It will also be seen that these chambers 14 and 15 are provided with fresh air inlets 16 and 17 respectively. By again referring to Figure 3 it will be seen that I have provided a secondary exit 18 leading to an ordinary chimney or flue. This secondary exit is provided with a damper 19 carrying an operating arm 20. This damper 19 is normally closed but in order to utilize the same an ordinary cord or chain is attached to point 21 on the operating arm 20.

The other end of this cord or chain to be attached to feed doors 22 and 23 so that when either or both of the feed doors 22 and 23 are opened the operating arm 20 will be drawn upwardly to a position shown in Figure 3 thereby opening the damper 19. The object of this secondary exit 18 is to provide efficient escape for smoke or gases directly to the flue or chimney when the furnace is being fired, it being understood that when the feed doors 22 and 23 are closed the

damper 19 automatically closes, due to the gravity pull on the operating arm 20 which is in a horizontal position when the damper 19 is open.

5 By referring to Figure 4 it will be seen that I have provided a top section 24 which is similar in shape to that of the second section 10.

10 By referring to Figures 1 and 4 it will be seen that I have provided upper outlets 25 and 26 leading into chambers 27 and 28 formed in the top section 24. It will be seen that I have provided a circular cap member 29 fitting securely over the interior circular member 11. The chambers 27 and 28 are separated by means of a partition 30 and a rectangular outlet chamber 31 positioned directly above the partition 30 and secured to the covering 32 of the top section 24.

15 By referring to Figure 4 it will be seen that this rectangular outlet chamber 31 is provided with an exit 33 leading to an ordinary flue or chimney. A bottom portion 34 of the rectangular outlet chamber 31 is provided with openings 35 and 36. These openings 35 and 36 being diagonally disposed into bottom portion 34 in such a manner that there is provided an opening on each 20 side of the partition 30. It will also be seen that I have provided a shut-off member 37 provided with a slide 38 which closes the opening 35 when the shut-off member 37 has been pushed in as shown in Figure 25 4. It will also be seen that when the shut-off member 37 is pulled outwardly the slide 38 closes the opening 36 and opens the opening 35.

30 The operation of the device is as follows:

40 The fire may be started over either grate 2 or 3 as desired. If the fire is started over the grate 2 the shut-off member 37 should be pulled out in order to close the opening 36 and open the opening 35. The fire now may be started over the grate 3 when the shut-off member 37 should be pushed in closing the opening 35 and opening the opening 36. The furnace should now be fired at intervals of such time as found 45 necessary to produce the desired heat, one grate being fired at a time and in order to secure maximum combustion of the fuel the openings 35 and 36 should be closed or opened in the manner described starting the 50 fire. In operating the furnace in the manner above described it will be seen that if fuel is placed upon the fire over the grate 3 the gases and smoke will be forced to take 55 a direction passing over the top of the hot

air manifold 6 where preheated air is 60 mingled with this smoke and gas being directed over the fire on the grate 2 where a maximum amount of the unburnt qualities of the fuel will be consumed. The refuse 65 consisting of incombustible gases etc. now passes through the curved and slotted partition 13 into the chamber 15, from which it passes into the chamber 28 and then 70 through to opening 36 and on out to an exit 33 leading to an ordinary chimney or 75 flue. It will be understood that by alternating the feeding over the grates 2 and 3 and manipulating the furnace as above described the passage of the combustible gases and the non-combustible gases will take alternating 80 courses to the final exit as above described.

What I claim is:

85 In a device of the class described the bottom section of a furnace carrying two sets of grates, an ash pit formed underneath said grates, a preheated hot air manifold positioned between said grates, a fresh air inlet leading into one end of said preheated hot air manifold, a ridge portion formed on the upper portion of said preheated hot air manifold, a plurality of openings distributed in the above mentioned ridge, a second section positioned above said grates and connecting parts, an interior circular member within 90 said second section, curved gratings secured to the sides of said interior circular section, a chamber communicating with said gratings, fresh air inlets leading into said chambers, a secondary outlet leading from the interior circular member, a damper functioning in said secondary outlet, a top section positioned above said second section, a circular cap member fitting securely over said interior circular member, two chambers formed in a top section, a vertical partition 100 separating said chambers, a rectangular outlet chamber formed directly above said partition, two openings formed in the bottom of said rectangular outlet circular, one opening on one side of said partition and another opening diagonally disposed and positioned on the other side of said partition, a slide functioning with said opening for the purpose of regulating the direction of non-combustible gases etc. escaping to an outlet leading to an ordinary chimney, substantially as described for the purpose set forth.

105 In testimony whereof I affix my signature.

JOHN A. HAGSTROM.
